UNITED STATES PATENT OFFICE

118,658

DESIGN FOR AN ARM FOR LAMP FIXTURES

August O. Elting, Chicago, Ill.

Application October 27, 1939, Serial No. 87,888

Term of patent 14 years

To all whom it may concern:

Be it known that I, August O. Elting, a citizen of the United States, residing at Chicago, in the county of Cook and State of Illinois, have invented a new, original, and ornamental Design for an Arm for Lamp Fixtures, of which the following is a specification, reference being had to the accompanying drawing, forming a part thereof, in which:

Fig. 1 is a plan view of the arm for lamp fixtures showing my new design.

Fig. 2 is a side elevational view.

Fig. 3 is an inverted plan view.

Fig. 4 is an end elevational view thereof.

I claim:

The ornamental design for an arm for lamp fixtures, as shown.

AUGUST O. ELTING.
